(57) **CLAIM**

The ornamental design for a chair with armrests, as shown and described.

DESCRIPTION

FIG. 1 is a front view of a chair with armrests showing the new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof according to first embodiment view thereof;

FIG. 8 is a perspective view thereof according to second embodiment view thereof;

FIG. 9 is a perspective view thereof according to third embodiment view thereof;

FIG. 10 is a perspective view thereof according to fourth embodiment view thereof;

FIG. 11 is a perspective view thereof according to fifth embodiment view thereof;

FIG. 12 is a perspective view thereof according to sixth embodiment view thereof; and,

FIG. 13 is a perspective view thereof according to seventh embodiment view thereof.

The broken lines shown in the figures are for the purpose of illustrating portions of the chair with armrests and form no part of the claimed design.

1 Claim, 13 Drawing Sheets
